UNITED STATES PATENT OFFICE.

EMERSON C. STRANGE, OF TAUNTON, MASSACHUSETTS.

MUSIC-RACK.

SPECIFICATION forming part of Letters Patent No. 230,446, dated July 27, 1880.

Application filed November 25, 1879.

To all whom it may concern:

Be it known that I, EMERSON C. STRANGE, of Taunton, State of Massachusetts, have invented an Improved Music-Rack, of which the following is a specification.

The object of my invention is to provide an inexpensive means of changing the position of the supporting-rack relatively to its supporting-rod; and the invention consists in 10 a head suitably formed to be secured to the supporting-rod, and having two planes oblique to each other, and which in their width are formed tapering from their base or lower end upward, and having beveled or retiring edges, 15 which interlock in a corresponding slot formed in the rack, which is thereby secured in position and supported.

Figure 1 is a side elevation of my invention as secured to a chair. Fig. 2 is a vertical section as taken on line Y Z, Fig. 1, with the chair omitted, and showing the pivoted socket and lower part of the tube in longitudinal section. Fig. 3 is a vertical section as taken in the axis of the sliding rod *i*, and 20 showing said rod, the upper portion of the tube in which it slides, and the socketed head formed with two planes, secured upon the projecting end of such rod. Fig. 4 is a transverse section as taken on line W X, Fig. 1, showing the said planes and the taper slot or groove 25 in the rack *m*, which engages the said planes. Fig. 5 is a top or plan view of one of the said planes, and showing the socket and part of rod *i*.

30 In these views, *a* represents the seat of the chair. *b* is the clamp, which is secured to the

chair by the screw *c*. *d* is a circular base, from which socket *e* proceeds. This base rests upon a corresponding bearing formed on clamp *b*, and is thereto secured by thumb-screw *f*. 40

g is a tube, secured in socket *e*, and at its upper end it is provided with the thumb-screw *h*, by which to lock in place rod *i*, which slides in the tube.

j is a socket, in which rod *i* is secured, and 45 as an extension of which two planes, *k l*, are formed, tapering or with converging side or edge lines, as shown in Fig. 5, and with undercut or beveled edges, as shown in Fig. 4, while the holding-rack *m* at its central part, *n*, is 50 provided with a slot or seat formed to correspond with and to receive either of said planes, as shown in Fig. 4.

By removing rack *m* and reversing rod *i*—that is, turning it half a circle in tube *g*—the 55 position of the rack when replaced will be changed in its relation to a horizontal line to the extent of the diversity of obliquity of said planes relatively to the axis of rod *i*.

I claim as my invention—

In a music-rack and book-holder, the adjustable rod *i*, having a head provided with planes *k l* and arranged oblique to each other, and formed with undercut and converging edge-lines, and a rack having a recess or seat to 65 interlock with such planes, substantially as specified.

EMERSON C. STRANGE.
